UNITED STATES PATENT OFFICE.

JOSEF BAYER, OF BARMEN, GERMANY.

SEAL FOR HOOP-IRON ENDS.

Application filed July 22, 1922. Serial No. 578,862.

To all whom it may concern:

Be it known that I, JOSEF BAYER, a citizen of the German Republic, and residing at Barmen-U., Germany, have invented certain new and useful Improvements in a Seal for Hoop-Iron Ends, for which I have filed an application in Germany April 1, 1921, and of which the following is a specification.

10 It is known to join the superposed ends of hoop-iron laid around chests, parcels, bundles, or the like, without perforating and without riveting the same, simply by cutting or punching tongues out of said ends and turning the same over. Thereby, the hoop-iron is, however, weakened in the same way as when perforating and riveting the same, which, owing to the high tensile strain to which the hoop-iron is exposed, reduces the tensile strength of the latter. Furthermore, means have become known, by which a hook-shaped punching-tooth provides incisions in the hoop-iron for producing said tongues therein, or which by 25 a double-acting punching-blade cut the tongues out of said hoop-iron ends, so that rivets or the like are not required.

Besides, it has been proposed to enclose the superposed hoop-iron ends to be joined 30 by means of a joining member and to severally press or squeeze the joint by a pressure that is exerted at right angles, or parallel, to the plane of the joint in such a way that on top of the joint a plurality of bulbs are 35 produced, which has the disadvantage that the latter form impediments thereon, while the production of said squeezed joint requires great expenditure of power. A further drawback of said joint consists in the 40 fact that the same can be varied by multiplying or modifying the lateral squeezings only.

The present invention provides an improved method, by means of which said 45 hoop-iron joint and seal is produced with the aid of such a joining member enclosing the superposed hoop-iron ends, said method consisting in providing said joint at its edges at a time with one or a plurality of finger-like impressions, of variable design, projecting 50 at an angle from the underside of the joint, and that by a pressure acting at right angles to the plane of the joint, while means are provided for further varying said joint 55 and seal and making the same particularly useful for the actual owner, by whom it is

employed, as well as for his customers. By the fingerlike impressions projecting at an angle from the underside of the joint, the upper side of the latter is left perfectly 60 smooth and thus forms no impediment whatsoever, while the downwardly projecting fingerlike edge impressions press themselves into the material of the chest or the like around which the hoop-iron is placed. 65

The accompanying drawings show how the invention can be put into practice:

Fig. 1 is a sectional side view of a pressure-contrivance for producing the edge impressions in the hoop-iron joint, the latter 70 being shown in its proper position therein.

Figs. 2 and 3 are plan views of the latter, respectively with the upper and lower part of the same in section;

Fig. 4 is a plan view of the joining member mentioned; 75

Fig. 5 is a plan view of the finished joint and seal with one fingerlike edge impression,

Figs. 6 and 7 are respectively an edge view and a side view of the latter. 80

Fig. 8 is a sectional side view of a double-acting pressure-contrivance combined with a hoop-iron stretcher,

Figs. 9 and 10 are plan views of the latter, respectively with the upper and lower 85 part of the same in section,

Fig. 11 is a sectional front view of the casing of the pressure-contrivance shown in Fig. 8,

Fig. 12 is an underside plan view of the 90 punch fitting in said casing, with the pressure-fingers thereon in section;

Fig. 13 is again a plan view of the joining member mentioned;

Fig. 14 is a plan view of the finished joint 95 and seal with two fingerlike edge impressions produced by the double-acting pressure-contrivance,

Figs. 15 and 16 are respectively an edge view and a side view of said finished joint. 100

Figs. 17 and 18 are plan views showing two modifications of the finished joint.

Fig. 19 is a sectional elevation of a punch by means of which a further modified joint and seal shown in Fig. 20 can be produced. 105

Figs. 21, 22 and 23 show further modifications of a joint and seal produced according to the present invention.

The pressure-contrivance shown in Figs. 1 and 8 comprises a vertically up and down 110 movable punch *d* with pressure-fingers *d*¹ at its lower end facing a correspondingly

shaped fixed matrix *a* with a support *b*, the hoop-iron to be joined being, with the joining member *g* on its superposed ends *f*, *f'*, placed edgeways between said support *b* and 5 said punch *d* and, by lowering the latter, provided with one fingerlike impression (Fig. 5) or with several such impressions at a time (Fig. 14) to be uniformly distributed over said joining member *g*, said impressions projecting then somewhat laterally from the plane of the joining member. 10

As shown in Fig. 17, the edge impressions may also be provided at the ends *g*² of the joining member *g*¹ only, which engage thus 15 the hoop-iron in hooklike fashion; or, as shown in Fig. 18, the edge impressions may be uniformly distributed over the joining member *g*¹, such as in Fig. 14, and besides provided at the ends *g*² of the same, such as 20 in Fig. 17.

As further shown in Figs. 17 and 18, the joining member *g*¹ may on its upper surface be provided with any particular designation, for instance the trade-mark of a 25 firm or the like, such as indicated by the words "Herko" or "Joba."

It will be seen that beside the great reliability of the hoop-iron joint and seal its variability is unlimited: either by providing 30 any number of edge impressions therein, or by varying the design of said impressions, so that, in connection with the particular designations on the upper surface of the joining member, the danger of a fraudulent removal of the joint and thus of theft is reduced to a minimum. 35

Figs. 19 to 24 inclusive illustrate constructional forms of further variations or 40 modifications of the joint and seal, whereby, besides, a particular strengthening of the latter is obtained.

In Fig. 20, the joint consists, as in Fig. 14, of a joining member 3 enclosing the 45 superposed hoop-iron ends 1, 2 and having the edge impressions 4 therein, while it is further provided with a U-shaped bend 5, which is produced therein by means of a punch 8, 9, 10 such as indicated in Fig. 19.

The middle part of the joining member 50 3 may also be somewhat compressed from both its edges between the two edge impressions 4, either in elongated fashion as shown in Fig. 21, or in circular fashion as shown in Fig. 22, 6 and 6^a indicating the 55 two punch members used for this purpose in the pressure-contrivance.

Instead of fingerlike edge impressions, 60 als such of elongated formation extending up to the ends of the joining member may be provided by means of corresponding punch members indicated at 7 in Fig. 23, whereby a crosslike joint of extreme strength is produced.

The multiple variations of the joint and 65 seal have the advantage that each owner

of the particular joint and seal, as well as his customers, can at once perceive a fraudulent manipulation on the original joint and seal.

What I claim, is:

1. A hoop-iron joint comprising two superposed hoop-iron ends and a joining member enclosing said ends, a smooth upper surface on said joint, and fingerlike depressions at both edges of the joint bent in 75 the same direction and projecting at an angle from the underside of the joint only, substantially as set forth.

2. A hoop-iron joint comprising two superposed hoop-iron ends and a joining 80 member enclosing said ends, a smooth upper surface on said joint, and fingerlike depressions at both edges of and uniformly distributed over the joint and bent in the same direction and projecting at an angle 85 from the underside of the joint only, substantially as set forth.

3. A hoop-iron joint comprising two superposed hoop-iron ends and a joining 90 member enclosing said ends, a smooth upper surface on said joint, and fingerlike depressions at both edges and at the ends of the joint and bent in the same direction and projecting at an angle from the underside of the joint only, substantially as set forth.

4. A hoop-iron joint comprising two superposed hoop-iron ends and a joining member enclosing said ends, a smooth upper surface on said joint, and fingerlike depressions at both edges of and uniformly distributed over the joint and bent in the same direction and projecting at an angle from the underside of the joint only and partly located at the ends of the joint, substantially as set forth.

5. A hoop-iron joint comprising two superposed hoop-iron ends and a joining member enclosing said ends, a smooth upper surface on said joint, fingerlike depressions at both edges of the joint bent in the same direction and projecting at an angle from the underside of the joint only, and a U-shaped bend at the middle of the joint, substantially as set forth.

6. A hoop-iron joint comprising two superposed hoop-iron ends and a joining member enclosing said ends, a smooth upper surface on said joint, and fingerlike depressions at both edges of the joint bent in the same direction and projecting at an angle from the underside of the joint only, the middle part of the joint between said edge depressions being compressed from both its edges, substantially as set forth.

7. A hoop-iron joint comprising two superposed hoop-iron ends and a joining member enclosing said ends, a smooth upper surface on said joint, and fingerlike depressions at both edges of the joint bent in the same direction and projecting at an angle 120 from the underside of the joint only, 125

from the underside of the joint only, the middle part of the joint between said edge depressions being compressed from both its edges in elongated fashion, substantially as set forth.

8. A hoop-iron joint comprising two superposed hoop-iron ends and a joining member enclosing said ends, a smooth upper surface on said joint, and fingerlike depressions at both edges of the joint bent in the same direction and projecting at an angle from the underside of the joint only, the middle part of the joint between said edge depressions being compressed from both its edges in circular fashion, substantially as set forth.

9. A hoop-iron joint comprising two

superposed hoop-iron ends and a joining member enclosing said ends, a smooth upper surface on said joint, and fingerlike depressions at both edges of the joint bent in the same direction and projecting at an angle from the underside of the joint only, said edge depressions extending from about the middle to the ends of the joint and forming a crosslike seal of extreme strength, substantially as set forth.

In testimony whereof I have hereunto set my hand in the presence of two subscribing witnesses.

JOSEF BAYER.
